PROCESS FOR MANUFACTURING A TYING MEMBER

Filed Sept. 25, 1942

UNITED STATES PATENT OFFICE

2,371,357

PROCESS FOR MANUFACTURING TYING MEMBERS

Walter R. Schindler, Los Angeles, Calif.

Application September 25, 1942, Serial No. 459,696

1 Claim. (Cl. 154—2)

My invention consists of a process and an automatic machine for manufacturing a tying member and more particularly to a machine for manufacturing a tying member composed of a lamination of paper, wire and asphalt.

My present invention is an improvement over that described in my prior patent for a similar subject No. 2,290,386 issued July 21, 1942.

The present process and machine has all of the advantages of my prior machine with the additional advantage that only one source of supply of paper is used and the same is doubled to secure the necessary laminations. By using one supply or continuous strip of paper in the place of the two strips in my previous patent I am able to place trademarks or other descriptive matter upon the finished tying member. This is not possible with the double paper supply as the markings on top and bottom of the tying member would not align with each other.

In general, my present invention consists of the process and machine for continuously feeding a wide strip of paper which is slit longitudinally, and then longitudinal strips folded substantially at their middle while feeding between each fold a continuous wire. The paper and wires are laminated together with a glueing substance preferably waterproof such as asphalt. By prior slitting of one sheet and folding the strips formed thereby, and by using a cut-off to cut off at a predetermined point, my machine is capable of carrying out the process of forming a plurality of tying members comprising flat bands of paper with a wire running through them, and the same are bound together with an adhesive.

My machine is entirely automatic and needs no supervision. An operator is needed only to start the machine after inserting the paper and wire and to package the finished article.

In the drawing:

Fig. 1 is a diagrammatic elevation illustrating my complete machine;

Fig. 2 is an end view of the folding rolls taken on the line 2—2 of Fig. 1;

Fig. 3 is an end view of the glue wheels taken on the line 3—3 of Fig. 1;

Fig. 4 is a cross section taken on the line 4—4 of Fig. 1;

Fig. 5 is a plan view of a tying member.

In the preferred form of my invention a plurality of tying members are made at one operation. To secure this plurality of finished members I use a wide strip of paper 1 carried on the spool 2. This is fed into my machine between the power driven feed rollers 3 and 4. The roller 3

is made of rubber or other substance to give it a grip on the paper 1. After passing through the feed rollers 3 and 4, the paper is divided into a plurality of narrow strips 8 by the slitting cutters 5 and then passed through the feed rolls 6 and 7 similar to rolls 3 and 4.

The individual strips 8 are then fed into the folding rolls 9 and 10 which comprise a pair of complementary rolls the lower roll 9 having its edge 11 tapered to form an inverted V and the upper roll having its edge 12 in the form of a complementary V. When the strips 8 are passed between the rolls 9 and 10, they are folded into a V shape.

After being folded the strips 8 pass through the guides 13 which comprise complementary V-shaped parts 14 and 15. At the apex of the V 15 a groove 16 is provided. Into these grooves the wires 17 are fed from the spool 18.

The strips 8 with the wires 17 between the folds thereof then pass between the tarring rolls 19 and 20. These rolls are identical with the rolls 9 and 10 with the exception that the rolls 19 have the grooves 21 to take the wires 17.

The lower side of the rolls 19 are immersed in the asphalt bath 22 which is heated by the burner 23. As the rolls 19 are rotated by the passage of the strips 8 between them they paint the molten asphalt on the wires 17 and strips 8. The strips 8 and the wires 17 are then combined by passing through the pressure rolls 24 and the cooling rolls 25 and the power-driven rolls 26, the latter being identical with the feed rolls 3 and 4.

While all of the rolls can be power-driven at the same speed by one motor, I prefer to drive only the feed rolls 3, 4, 6, 7 and 26.

The slitting cutter 5, the pressure rolls 24 and the cooling rolls 25 are the same as described in my prior Patent No. 2,290,386 and all of the rolls can be journaled as shown therein.

I prefer to place idler rolls 27 on the paper supply 1 to maintain the paper taut and idler rolls 28 similarly maintain the wire 17.

To prevent waste of material the shut-offs 29 and 30 on the paper supply 1 and the wire supply 17 are used. These shut-offs are identical with those on my prior machine described in Patent No. 2,290,386. These shut-offs stop the machine if the paper is torn or a wire broken.

A feature of my present invention is that trademarks or other brands 31 can be printed on the roll of paper and when folded in the machine

the tying members will always have the brands 31 opposite each other.

To cut the tying members to a correct size the paper 1 has marks 32 placed thereon during the printing of the brand. These marks 32 when passed under the ordinary electric eye 33 actuate the eye which energizes the solenoid 34 causing the same to draw down the knife 35 by means of the links 36. The knife 35 cooperates with the shear block 37 to cut the strips 8 to the desired length. After each stroke of the knife 35 it is returned to its original position by the spring 38. This length is fixed by the position of the mark 32 and the strips 8 are cut substantially equidistant from the ends of the brand 32.

While I have described the preferred embodiment of my invention, I am not limited to the details thereof except as set forth in the following claim.

I claim:

The process of forming tying members having a printed legend thereon, comprising passing a roll of paper having printed thereon legends in a continuous strip through a slitting device and thus dividing said roll into a plurality of narrow strips, said division separating said legends longitudinally, folding said narrow strips longitudinally substantially at their center lines, simultaneously feeding a wire between the folds of each strip, and painting the wire and interior of the folds with an adhesive, then feeding said strips through pressure rolls to permanently unite said folded members with said wire and adhesive, and cutting said strips transversely between said legends to provide a printed legend on each tying member.

WALTER R. SCHINDLER.
